ART OF MAKING FASTENER ELEMENTS

Application filed December 22, 1924. Serial No. 757,322.

My invention relates to fasteners of the quick-operating type which are designed to be interlocked and released by movement of a slider therealong, and has reference more particularly to the method of forming an elongated coiled fastener element with one or more offsets or bends in each convolution, which serve to afford an interlocking engagement with another elongated coiled element.

10 A highly satisfactory quick-operating fastening device is obtained by arranging elongated coiled elements side by side and nesting the coils of one of the elements between the coils of the other element, provided that the nested portions of the coils of one of the elements are suitably bent or offset so as to interlock with the coils of the other element. The spacing between the coils must be substantially equal to the diameter of the wire of which the coils are formed, so that there is practically no looseness or play in an axial direction between the enmeshed coils of the elements, and for the purpose of holding the coils in proper spaced relation, the sides thereof remote from the points of interlocking engagement are secured to a non-stretching tape or other suitable flexible member which prevents axial elongation of the coiled elements. In practice, it has been found that a particularly effective fastener element results when each convolution of the coiled element is provided with a plurality of reverse bends or waves extending alternately in opposite axial directions, as this affords a circumferential series of interlocking points, permitting interlocking engagement at any place therearound and maintaining such engagement when the other element is shifted around the element having the adjoining bends. Moreover, such formation affords a bend in each convolution at the point of attachment to the tape and tends to prevent circumferential displacement of the coils on the tape.

45 It will be understood from the foregoing that a high degree of accuracy is required in forming the spiral elements so that the bends will align and the proper spacing is maintained between the coils, and as the wire used in such fastener elements is necessarily

small gauge, it is desirable to avoid abrupt bends or die markings which would weaken the wire and make it subject to breakage in use.

The principal objects of my invention are 55 to provide a coiled fastener element with suitable bends accurately arranged so as to afford an effective interlocking element; to construct the spring with a plurality of reverse bends or waves in each convolution which 60 are uniform and in axial alignment; to provide a method which may be utilized for forming bends of any desired form and number in the convolutions of a coiled element; to avoid stamping or excessive bending of 65 the wire which would weaken the completed fastener element; and in general, to simplify, reduce the expense of manufacture and insure accuracy and uniformity in the construction of fastener elements of the type 70 above referred to.

On the drawings:

Fig. 1 is a fragmentary view of a fastening device of the character to which my invention relates, showing the opposed spiral elements in the interlocked and released positions respectively, below and above the operative slider;

Fig. 2 is a fragmentary view of rolls for crimping the wire preparatory to forming 80 same into a spiral coil;

Fig. 3 is a side view of a mandrel having a coiled element thereon at the completion of the winding operation;

Fig. 4 is similar view, showing the coiled 85 member on the mandrel after the waves or bends of the various convolutions have been lined up;

Fig. 5 is an end view of a finished coiled element constructed in accordance with my invention, and

Fig. 6 is a view, somewhat diagrammatic, showing the manner in which tension is afforded for effecting a uniform opening up of the bends as the crimped wire is wound on 95 the mandrel.

Referring to the drawings, the reference numerals 1 and 2 indicate fragmentary portions of rolls which are geared together in the usual manner to afford a positive driv-

ing connection therebetween and suitably operated to crimp or form reverse bends in the wire 3. These rolls are preferably formed with spaced projections 4 somewhat in the form of gear teeth, which are arranged so that as the rolls are rotated, the teeth of one roll enter midway between the adjoining teeth of the other roll, thereby forming the reverse bends 5 and 6 respectively, which 10 bends, while quite pronounced, are well rounded so that no breaking strain is imposed on the wire.

After the wire has been crimped or formed with the bends 5 and 6 as shown in Fig. 2, the crimped wire is wound on a mandrel 7. This mandrel may be arranged to be rotated in any convenient manner and preferably has an aperture 8 to receive the ends of the crimped wire for holding the same as the 20 winding is started on the mandrel. Suitable mechanism is provided to direct the wire onto the mandrel and advance the same along the mandrel as the latter is rotated so that a space occurs between successive coils which 25 is substantially equal to the diameter of the wire. The wire is of course guided onto the mandrel so that the reverse bends lie flat against the surface of the mandrel and extend respectively toward the opposite ends of 30 the latter, and the wire is held under a tension which serves to open up the bends 5 and 6 of the wire uniformly so that they assume a wave-like formation somewhat as shown at 35 9 and 10 Fig. 3. The required tension may be afforded as shown in Fig. 6, by feeding the crimped wire from the rolls 1 and 2 so that the crimps extend upwardly and downwardly, or lie in a vertical plane, and providing the 40 guide 16 which directs the wire onto the mandrel with a horizontal slot which turns the crimped wire so that the crimps lie in a horizontal plane as the wire feeds onto the mandrel. This quarter turning of the 45 crimped wire and drawing same through the slot of the guide 16 has been found to effect a uniform opening of the bends and insures proper relative positioning of the waves on the mandrel. The crimped wire may, of 50 course, be prepared previous to the winding operation and fed from a spool or other source of supply in a manner to insure the required quarter-turn or other means may be provided for uniformly opening up the crimps as the coil is wound.

55 The wire is preferably wound on the mandrel so that a plurality of wave-like elements occur in each convolution of the wire, and it is desired that corresponding waves of all the convolutions shall be arranged in alignment lengthwise of the coiled element when the latter is completed. In order to accomplish this result, the wire is wound on the mandrel so that the corresponding waves of each convolution are advanced 60 or run somewhat ahead of the correspond-

ing waves of the preceding convolution and the corresponding waves of the convolutions are arranged in spiral lines somewhat as indicated at 11 in Fig. 3. After the winding of the spring has been completed, the final 70 end, which is the end indicated at 12 in Fig. 3, is held while the mandrel is turned back sufficiently in a direction reverse to that of the winding operation so that when the coiled element is freed, the corresponding waves or bends of the various coils are in axial alignment lengthwise of the coiled elements as shown in Fig. 4. The coiled element is then removed from the mandrel and is ready for use.

Fig. 1 shows the manner in which elements of this character are intended to be used, that is, the coiled element which has just been described, serves as a fastener element 13 which co-operates with another fastener element 14, the latter being preferably a plain coil so that the elements 13 and 14 interlock by nesting of the coils of one element between the coils of the other element when the slider 15 is moved therealong in one direction, and these coils likewise release when the slider is moved in the reverse direction.

In the illustrated construction, each convolution of the coiled element 13 has four bends 9 in one direction and four bends 10 in the other direction. However, it is to be understood that the number of bends is not important, as the same method of manufacture may be advantageously employed to form a coiled element with a single crimp or bend of any desired character or extent or in fact, any number of bends.

It will be noted that while the corresponding bends of the successive coils run somewhat in advance of the corresponding bends of the preceding coils, nevertheless they are sufficiently near to an axial aligning relation so that the bends of each convolution may nest within the corresponding bends of the adjoining convolutions and because of this feature, it is possible to wind the element with pronounced bends and at the same time have a close spacing of the coils or convolutions.

While I have shown and described my invention in a preferred form, I am aware that various changes and modifications may be made without departing from the principles of my invention, the scope of which is to be determined by the appended claims.

I claim as my invention:

1. The method of manufacturing a coiled fastener element of the class described, which comprises forming bends in a length of wire at regular intervals and then winding the wire on a mandrel so that each bend lies flat against the surface of the mandrel and is interposed between and spaced from corresponding bends of the adjoining convolutions.

2. The method of making a coiled fastener

- element of the class described, which comprises forming a length of wire with corresponding bends at regular intervals, then winding the wire on a mandrel so that each convolution comprises a bend which is interposed between corresponding bends of the adjoining convolutions and then untwisting the element and thereby fixing the bends in alignment along a line parallel to the axis of the coiled member. 5
3. The method of making a coiled fastener element of the class described, which comprises forming a wire with a plurality of uniformly spaced bends, then winding the wire 10 on a mandrel so as to form an elongated coil and simultaneously stretching the wire and thereby expanding the bends into wave-like formations with the wave-like formation of each convolution interposed between corresponding wave-like formations of the adjoining convolutions. 15
4. The method of making a coiled fastener element of the class described, which comprises forming a length of wire with uniformly spaced bends in the same plane, then winding the wire on a mandrel in separate spaced convolutions so that the bends lie flat against the surface of the mandrel and are offset in the direction of the length of the 20 mandrel. 25
5. The method of making a coiled fastener element of the class described, which comprises forming a length of wire with oppositely offset portions at regular intervals and then coiling the wire on a mandrel so that each convolution is separated from the adjoining convolutions and comprises a plurality of reversely offset portions in axial alignment with the corresponding offset portions of the other 30 convolutions of the coiled element. 35
6. The method of making a coiled fastener element of the class described, which comprises winding a wire on a mandrel in a zig-zag course so that each convolution is separated from the adjoining convolutions a distance substantially equal to the thickness of the wire and comprises alternate reverse bends which are interposed between corresponding bends of the adjoining convolutions 40 of the coiled element. 45
7. The method of making a coiled fastener element which comprises coiling a wire with alternate bends to form an elongated cylindrical spiral spring with corresponding portions of each convolution offset lengthwise of the spring and with an open space between the adjoining convolutions substantially equal to the thickness of the wire. 50
8. The method of making a coiled fastener element which comprises providing a length of wire with interlocking means at intervals, and then coiling the wire in the form of an elongated coiled spring with the interlocking means substantially in alignment lengthwise 55 of the spring, and with an open space between 60
- the adjoining convolutions substantially equal to the thickness of the wire. 65
9. The method of making a wire fastener element of the class described with spaced fastener loops or convolutions, which comprises successively providing successive portions of a length of wire with correspondingly arranged fastener deformations and simultaneously forming the wire into successive spaced loops of an elongated coil with the deformations separated from and located between corresponding deformations of adjoining coils or convolutions. 70 75
